UNITED STATES PATENT OFFICE.

WALTER BROWN, OF RACINE, WISCONSIN, ASSIGNOR, BY MESNE ASSIGNMENTS, TO WEBSTER ELECTRIC COMPANY, OF RACINE, WISCONSIN, A CORPORATION OF WISCONSIN.

MAGNETO-MACHINE.

1,330,165.

Specification of Letters Patent. Patented Feb. 10, 1920.

Application filed January 19, 1918. Serial No. 212,581.

To all whom it may concern:

Be it known that I, WALTER BROWN, a citizen of the United States, residing at Racine, in the county of Racine and State of Wisconsin, have invented a certain new and useful Improvement in Magneto-Machines, of which the following is a full, clear, concise, and exact description, reference being had to the accompanying drawings, 10 forming a part of this specification.

My invention relates to an improvement in magneto electric machines, and briefly stated the objects of my invention are to produce a more serviceable and durable device of this class that may be economically manufactured.

The machine herein described is characterized by the rigid and moisture proof nature of its stator elements, as well as by the 20 simple and extremely rigid construction of its rotor or armature.

In the accompanying drawings illustrating my invention:

Figure 1 is a view of a rotary low tension magneto, parts of the device being shown in section and other parts in elevation to more clearly illustrate the construction;

Fig. 2 is a vertical sectional view taken on the line 2—2 of Fig. 1;

Fig. 3 is a horizontal sectional view taken on the line 3—3 of Fig. 1; and

Fig. 4 is a perspective view of the magneto frame.

Similar characters of reference refer to 35 similar parts throughout the several views.

Referring first to Fig. 1, I have illustrated a magneto frame 9, which is a die casting and so conformed as to inclose pole pieces 10, 10. It will be seen that the pole pieces 40 and magneto frame are in effect one, for the reason that the frame is cast around and in contact with the pole pieces. The frame 9 carries an end plate 11, provided with a bearing 12 disposed centrally with respect 45 to the end plate. The frame also carries on each side thereof a shelf 14 and side pieces 15, 15 arranged to support field magnets 16, 16, around which a metallic band 17 is disposed and secured on either side of the 50 base 19 carried by the frame. The upper portion of the frame carries a hollow boss 21, into which is inserted a combination brush holder and conductor terminal clip, as will be presently described. The end 55 plate 11 has contained within it an oiling

device 22, which consists of a wad of cotton material soaked with lubricating oil, the oil being inserted into the device at 23. A ball seating against the wall surrounding the aperture 23 is held in place by a spring, and by this means dust is prevented from entering the oiling device 22. Carried on the opposite end of the magneto frame is an end plate 25 containing a bearing 26 and an oiling device 27, which is the same in construction as the one just described.

Journaled in the bearings 12 and 26 is a shaft 29 of a rotor or armature structure of novel and extremely rugged construction. The shaft, which is formed in one solid 70 piece, is tapered and threaded at one end to facilitate connection therewith of the usual driving gear. Disposed upon the shaft 29 is a coil carrying core consisting of a plurality of substantially I-shaped laminæ 30, 30, 75 each of which comprises two segmental end portions conformed to coöperate with the concave pole faces, each of said laminæ also comprising an intermediate portion connecting the said segmental end portions and integral therewith, the said intermediate portions of the laminæ 30, 30 being provided with central apertures through which the one piece shaft 29 of the armature structure extends.

Disposed on each side of the segmental ends of the core laminæ 30, 30 are the segmental laminæ 30^a, 30^a, which coöperate with the ends of laminæ 30, 30 to provide segmental armature faces of a length substantially equal to the length of the magnet pole faces. Having central apertures through which the shaft 29 extends, and embracing the armature laminæ between them are plates 33 and 34, the said plates and laminæ 95 being rigidly connected together by rivets, as most clearly illustrated in Fig. 2.

Although two coils are used in this armature, I have found it desirable to utilize but one piece of wire, for in this way it becomes 100 unnecessary to connect two or more wires, and eliminates the possibility of a break or a poor connection, due to defective joints. It will be noted that each of the armature core laminæ 30, 30 is provided with four 105 projections 31, 31 and that inasmuch as the core laminæ are disposed side by side, these projections 31, 31 constitute in effect shoulders between which and the segmental portions of the armature laminæ are wound the 110.

coils 32. The plate 34 functions as a collector plate for the ground connections, as will presently appear. A collector disposed adjacent to but insulated from the rest of the 5 armature is shown at 36. This collector consists of a ring 37, around which is molded a disk of insulating material 38, which also has contained within it a metallic hub 39, which is mounted on the shaft. The collector 10 is driven by a hollow boss protruding from and forming a part of the insulating disk 38, which hollow boss extends into an aperture carried by the plate 33. One end of the armature coil is inserted through this 15 hollow boss and attached to the ring forming a part of the collector, as shown at 41, Fig. 3. The other end of this coil is attached to the plate 34, as shown at 42 (Fig. 3). Carried by the end plate 11 are two 20 sockets each carrying a spring pressed brush 43, 43, engaging the ground collector plate 34. These brushes are preferably formed of carbon, but may be of any other suitable composition. Inserted within the hollow 25 boss 21 is a combined brush holder and conductor terminal clip 45, of the type shown and described in my copending application Serial No. 212,580, filed January 19, 1918, which consists of a piece of flat metal bent 30 into tubular conformation at one end to contain the brush of carbon 44, and at the other end to constitute a conductor terminal clip 46 of the type wherein a spring portion cooperates with a resistant portion to grip a 35 conductor. The end comprising the brush holder has molded around it a sleeve of insulating material 47, so that it is impossible to insert the brush holder and terminal clip without it being perfectly insulated from 40 the frame of the magneto. The sleeve carries means consisting of a projection 48 fitting into a recess 49 in the boss 21, whereby rotation is prevented, and it also carries an annular flange 50, so that by means of a nut 45 51 it is possible to hold the same securely in position.

As will be seen, the nut 51 is screw-threaded, and when adjusted the flange of the insulating sleeve is disposed between the nut and boss and securely held. If desired a 50 suitable gasket may be placed between the boss and flange to insure a watertight joint.

Having thus described my invention, what I claim as new and desire to secure by Letters Patent of the United States is: 55

1. A magneto comprising, in combination with a frame, field magnets and pole pieces therefor, a rotor structure consisting of a one piece shaft, a plurality of substantially I-shaped laminæ, having segmental ends, 60 constituting a coil carrying core, said I-shaped laminæ having central apertures, through which said one piece shaft extends, a plurality of segmental laminæ disposed on both sides of each end of the core formed by 65 said I-shaped laminæ, and with the latter forming segmental armature faces of substantially the same length as the pole pieces, together with means for rigidly securing all of said laminæ together. 70

2. A magneto comprising a rotor structure consisting of a pair of spaced disks having central apertures therein, a plurality of substantially I-shaped laminæ constituting a coil carrying core, said coil carrying core 75 disposed midway between said disks, said I-shaped laminæ having central apertures, a plurality of segmental laminæ disposed between said disks and the ends of said core, and with the ends of said core forming seg- 80 mental armature faces, a one piece shaft extending through the apertures in said disk, and through the apertures in said I-shaped laminæ, and rivets rigidly securing said disks and all of said laminæ together. 85

In witness whereof, I hereunto subscribe my name this 12th day of January, A. D. 1918.

WALTER BROWN.
